DESIGN FOR SCISSORS

George J. Staab, Springfield, N. J.

Application March 25, 1947, Serial No. 137,846

Term of patent 3½ years

(Cl. D22—5)

To all whom it may concern:

Be it known that I, George J. Staab, a citizen of the United States of America, and a resident of Springfield, in the county of Union and State of New Jersey, have invented a new, original, and ornamental Design for Scissors, of which the following is a specification, reference being had to the accompanying drawings, forming a part thereof.

Fig. 1 is a front elevational view of scissors showing my new design;

Fig. 2 is a top end view;

Fig. 3 is a side elevational view; and

Fig. 4 is a bottom end view of the scissors.

I claim:

The ornamental design for scissors, as shown.

GEORGE J. STAAB.
